UNITED STATES PATENT OFFICE.

BENJAMIN BELEFANT, OF BROOKLYN, NEW YORK.

CONDIMENT-HOLDER.

1,322,752.

Specification of Letters Patent. Patented Nov. 25, 1919.

Application filed August 13, 1918. Serial No. 249,752.

To all whom it may concern:

Be it known that I, BENJAMIN BELEFANT, a citizen of the United States, residing at Brooklyn, in the county of Kings and State 5 of New York, have invented certain new and useful Improvements in Condiment-Holders, of which the following is a specification.

This invention has relation to condiment holders, and has for an object to provide a 10 holder of the type including a single container adapted to contain different kinds of condiments or seasoning agents, with a sprinkler top, and means for permitting the discharge of only one kind of condiment at 15 a time.

A still further object of the invention is to provide a condiment holder of the character above described including a sprinkler top, a handle for conveniently manipulating 20 the holder, and a convenient means located in proximity to the handle whereby, the sprinkler top may be operated to insure the discharge of the condiment selected, to permit the discharge of all the different 25 kinds of condiments simultaneously, and to readily control the flow thereof.

A still further object of the invention is to provide a condiment holder having the characteristics above set forth which will at 30 the same time be of an extremely simple construction, permitting its economical manufacture.

In addition to the foregoing, this invention comprehends improvements in the 35 details of construction and arrangements of the parts, to be hereinafter set forth and particularly pointed out in the appended claims.

In the accompanying drawings in which 40 similar and corresponding parts are designated by the same characters of reference, throughout the several views in which they appear:

Figure 1 is a view in perspective of a condiment holder constructed in accordance with 45 my invention.

Fig. 2 is a view thereof in vertical section, and

Fig. 3 is a view thereof in top plan.

With reference to the drawings, 10 indicates a container which may be of porcelain, glass or any other desirable material, formed in an ornamental manner and provided with the handle 11. Surrounding the mouth of 50 the container is a band 12 of rigid material having a pair of sleeves 13 formed thereon

at diametrically opposite points. Mounted upon the band is a pair of semi-circular plates 14 and 15, each having a pair of apertured lugs 16 formed upon their diametrical 60 edges, with said lugs arranged in interlocking relation, and located between the sleeves 13 and a pin 17 inserted through the sleeves and lugs to secure the plates to the band in the manner shown. A coiled spring 18 encircles the intermediate portion of the pin with the ends thereof bearing upon the plates to secure the latter in closed position. Each plate is formed with small apertures 65 for the discharge of the condiment, and mounted upon the under side of each plate is a circular plate or disk 19 and 20, a rivet 21 serving to pivotally connect the disks in each instance with the plates to permit rotary movement of the disks. Each plate 14 70 and 15 is furthermore formed with a slot curved concentric relative to the rivets 21, and each disk is formed with a radial arm 22 which projects through the slots, the arms being offset for that purpose. The mouth 75 of the container may be formed with an annular groove in which to receive a ring 23 of yieldable material to form a packing or tight closure for the plates.

In operation, the handle is grasped and 80 one or the other of the arms 22 shifted by means of the thumb of the hand holding the container. The disk 19 or 20 as the case may be is thus rotated until its apertures are in registration with the apertures of the 85 plate and the condiment will then pass through. It will be noted that a partition 24 is provided within the container defining two compartments, each being controlled by one of the plates 14 or 15. Thus salt 90 may be placed in one compartment and pepper in the other, manipulation of the disks permitting the discharge of either condiment or both simultaneously.

While I have illustrated and described 100 my invention with some degree of particularity, I realize that in practice various alterations therein may be made, and I therefore reserve the right and privilege of changing the form of the details of construction and arrangement of the correlated parts, without departing from the spirit of the invention and the scope of the appended 105 claims.

1. A condiment holder including a container divided into two compartments, a band encircling the mouth of the container,

a pair of semi-circular flaps connected together at their straight edges and connected to the band for relative movement, a coiled spring urging the flaps apart and in 5 a position to cover the compartments, one of said flaps having a recess in its upper surface, and a projection in the other flap to enter said recess when the flaps are brought together to retain said flaps in an uncovered 10 position.

2. A condiment holder including a container formed with a partition to define two compartments, the mouth of the container having a rounded edge, a band to 15 encircle the mouth of the container and to closely fit said edge, a pair of diametrically opposed ears formed on said band, a pair of semicircular perforated flaps each having ears formed upon their straight edges for

interfitting engagement with each other 20 and for interfitting engagement with the first mentioned ears, a pintle penetrating said ears, a spring surrounding the pintle and engaging the flaps to retain them in a position to cover the compartments, the inner portion of the mouth of the container having an annular groove, a packing ring seated in said groove to contact with the flaps, a pair of perforated disks pivoted to the inner sides of the flaps, and means for 25 30 rotating said disk.

In testimony whereof I affix my signature in presence of two witnesses.

BENJAMIN BELEFANT.
